SHEET METAL SHAPER

Filed Dec. 11, 1939

UNITED STATES PATENT OFFICE

2,260,624

SHEET METAL SHAPER

Albert S. Johann, Milwaukee, Wis., assignor to
 Milwaukee Electric Tool Corporation, Milwaukee,
 Wis., a corporation of Wisconsin

Application December 11, 1939, Serial No. 308,621

2 Claims. (Cl. 153—48)

The present invention relates generally to improvements in the art of shaping sheet metal and relates more particularly to improvements in the construction and operation of portable tools especially adapted to restore or re-shape damaged sheet metal automobile parts such as bodies, fenders and the like.

An object of the invention is to provide an improved sheet metal shaper or former, which is simple and compact in construction, and which is moreover highly efficient and flexible in use.

Many different types of tools and appliances have heretofore been utilized in the automobile repair industry to restore damaged sheet metal parts such as bodies and fenders, to normal condition. It is customary in repairing dented sheet metal parts, to bump out the dents or kinks to the approximate original position of the metal, and to subsequently iron out the rough spots with a portable pneumatically operated repair tool or assemblage having a yoke of desirable shape, one end of which carries an anvil block, and to the other end of which is secured a pneumatic hammer cooperating with a dolly or plunger coating with the anvil through the distorted area of the sheet metal which is being straightened. While the yokes of these prior pneumatic sheet metal straightening tools can be moved about so as to cause the dolly and anvil to travel along the distorted areas, they cannot be freely tilted and rotated about the axes of the impact and reaction element of the hammer assemblage, thus making it difficult and sometimes impossible to advance the tool in every desired direction and at variable angles so as to form smooth curves. The prior assemblages are also rather difficult to position with reference to some classes of work and in relatively inaccessible places, and therefore do not meet many requirements and cannot be readily manipulated to quickly produce a smooth ironing job at diversely curved areas of the sheet metal.

It is therefore a more specific object of my present invention to provide an improved portable pneumatic hammer assemblage wherein the anvil and impact pin or dolly cooperating therewith are freely rotatable with respect to the hammer axis, and are also freely tilttable relative to the carrier yoke, whereby smoother ironing is made possible and manipulation of the assemblage is greatly facilitated.

Another specific object of the invention is to provide various improvements in the construction of portable hammer units, whereby such tools may be readily and quickly applied to the work

and manipulated in relatively inaccessible places.

A further specific object of my invention is to provide a compact and durable portable sheet metal straightening tool which is conveniently manipulable to most effectively perform different classes of work, and which is especially adapted to produce smooth curvature of sheet metal in any desired direction.

Still another specific object of this invention is to provide a new and useful pneumatic hammer assemblage wherein the hammer cylinder may be quickly and positively withdrawn from or advanced toward the work, and in which excessive play is eliminated between movable parts of the assemblage.

An additional specific object of the invention is to provide improved means for retaining the portion of the sheet metal which is being operated upon by a pneumatic hammer or the like in contact with the anvil, and for preventing excessive vibration and stresses resulting from tilting of the manipulating frame relative to the anvil and impact pin.

These and other specific objects and advantages of my invention will be apparent from the following detailed description.

A clear conception of the several features constituting my present improvement, and of the mode of constructing and of manipulating a sheet metal shaper built in accordance with the invention, may be had by referring to the drawing accompanying and forming a part of this specification wherein like reference characters designate the same or similar parts in the various views.

Fig. 1 is a side elevation of one of the improved portable sheet metal shapers, showing the hammer actuated dolly brought into contact with the anvil;

Fig. 2 is an enlarged central longitudinal section through the pneumatic hammer and the anvil, showing the dolly in contact with the anvil; and

Fig. 3 is a transverse section through the assemblage of Fig. 2, taken along the line 3—3.

While I have shown and described one commercial embodiment of my improved portable shaper, it is not the intent to unnecessarily restrict the scope or utility of the invention, and it is to be understood that the hammer and anvil supporting frame may be of diverse shapes depending upon the specific use of the tool.

Referring to the drawing, the improved portable sheet metal shaper shown therein comprises in general, a tubular C-shaped frame 6 having

one approximately vertical end 7 and another approximately horizontal end 8; an anvil or reaction block 9 universally movably supported upon the vertical frame end 7 by means of a pivot element 10; a dolly or pressure block 11 cooperable with the anvil block 9 and being universally movably suspended from the lower headed end 12 of an impact pin 13; a pneumatic hammer assemblage consisting of a cylinder 14 and a plunger or piston 15, within which the pin 13 is removably confined; a fitting 16 detachably secured to the horizontal frame end 8 by means of a clamping bolt 17, and having a bore 18 within which the hammer cylinder 14 is snugly but slidably confined; and an adjusting pinion 19 rotatably mounted within the fitting 16 and coacting with rack teeth 20 on the cylinder 14, to positively move the hammer assemblage and the associated parts toward or away from the anvil block 9.

The frame is preferably formed of a relatively rigid but light steel tube, and the pivot element 10 may be either permanently or detachably secured to the vertically directed frame end 7 in any desired manner. The element 10 has a head 21 at its upper end provided with a spherical zone surface with which the anvil block 9 coacts as shown in Fig. 2; and the block 9 is rectangular in shape and is provided with a centrally flat and marginally convexly curved surface 22 which is preferably curved in all directions away from the flat area and is rounded at its edges as shown in Figs. 1 and 2. The anvil block 9 is freely rotatable and slightly tiltable in all directions, upon the spherical zone surface 21 of its supporting element 10, and may be replaced for performing different work by other anvils of different shapes and sizes. The dolly block 11 which is cooperable with the anvil block 10 through the work, has a conical central recess with which a lower spherical zone surface 23 on the head 12 of the suspension pin 13 coacts so as to permit both free rotation and limited tilting of the block 11 in all directions, in unison with the reaction block 9; and the dolly or block 11 is permanently suspended from the pin head 12 by means of a retaining collar 24, see Fig. 2. The dolly block 11 is circular in shape and is also provided with a centrally flat and marginally concavely curved surface 25 corresponding in shape to that of the anvil surface 22, and this surface 25 is surrounded by an annular depending lip 26 spaced from and surrounding the surfaces 22, 25 and adapted to contact the upper surface of the intervening work sheet. As shown in Figs. 1 and 2, the annular lip 26 is rounded and extends downwardly beyond the plane of the lower edge of the surface 25, but not below the plane of the curved lower edges of the surface 22, so that the lip 26 will always properly engage the work and will position the ironing surfaces 22, 25 so as to most effectively cooperate with the area of the work being operated upon.

The pneumatic hammer comprising the cylinder 14 and the plunger 15, is disposed in axial alignment with the impact pin 13; and the cylinder 14 is provided with a central bore 27 in which the plunger 15 is reciprocable. The lower end of the bore 27 is normally closed by a removable bushing 28 in which the impact pin 13 is snugly but slidably confined, and the pin 13 has an annular groove 29 with which a latch pin 30 coacts to normally retain the pin 13 within the bushing 28. The groove 29 should be of sufficient width to permit the impact pin 13 to move axially relative to the bushing 28 and cylinder 14, and the

latch pin 30 should not interfere with this movement and is held in place by a light spring 31 so as to permit the pin 13 and dolly block 11 to be readily withdrawn endwise from the bushing 28.

5 The portion of the dolly suspension pin 13 between the bushing 28 and the pin head 12, is embraced by a collar 32, the lower end of which engages the head 12, and the upper end of which has an integral stop flange adapted to engage the lower end of the bushing 28; and the upper extremity of the pin 13 projects slightly above the upper end of the bushing 28 and into the cylinder bore 27.

10 The hammer plunger 15 fits snugly within the main cylinder bore 27, and has a reduced integral upper end extension 33 which is reciprocable within a reduced bore 34 in the cylinder 14 to provide a cushioning chamber 35 above the impact piston. A central passage 36 within the plunger 15, leads from the lower plunger displacement chamber 37 to a point above the upper displacement chamber 38; and is communicable through a lateral port 39, with a compressed air supply duct 40 formed in the cylinder 14 and 15 communicating with a flexible air supply pipe 41. The upper reduced portion of the plunger 15 is also provided with an annular groove 41' which establishes communication between the duct 40 and the chamber 38 when the plunger 15 20 is lifted. The lower and upper displacement chambers 37, 38 are respectively communicable through ports 42, 43 with a groove 44 formed in the cylinder 14 and communicating with the ambient atmosphere, and when the various parts of 25 the hammer are in the position shown in Fig. 2, the passage 36 is sealed by the pin 13 and the hammer 15 must be lifted before air can be admitted to either of the plunger displacement chambers 37, 38. The air supply pipe 41 should 30 also be provided with a cut-off valve so that the air can be shut off when the tool is not in use.

35 As previously indicated, the hammer cylinder 14 and the parts carried thereby, are slidably in the vertical bore 18 of the fitting 16, by means of the pinion 18 coacting with the rack teeth 20 formed on the cylinder 14. The pinion 19 is secured to a shaft 45 by a key 45', and the shaft 45 is journalled in the fitting 16 and in a removable plug 46 coacting with the fitting to normally confine the pinion 19. The shaft 45 has a central bore 47 extending inwardly from one end, and also has an actuating crank or handle 48 secured to its opposite end; and the end of the pinion 19 facing the plug 46 is provided with an annular series 50 of radial ratchet teeth 49 adapted to coact with a similar series of teeth formed on the adjacent side of an annular member 50 which is slidable along the shaft 45 between the pinion 18 and plug 46. The member 50 while being movable 55 toward and away from the pinion 19, is locked against rotation with the shaft 45 by means of spline projections 51 formed integral with the plug 46 and engaging diametrically opposite slots 51' formed in the member 50. The two sets of 60 teeth are constantly urged toward interlocking position as shown in Fig. 3, by means of a compression spring 52 interposed between the plug 46 and the member 50; and the member 50 is adapted to be forced to the right and out of engagement with the pinion 19 as viewed in Fig. 3, by means of a plunger 53 located within the shaft bore 47 and having a button 54 at one end, and prongs 55 at its opposite end projecting through slots 56 in the medial portion of the shaft 45. 65 With this assemblage of elements, the pinion 19 is

constantly drivingly connected to the shaft 45 by the key 45', and the member 50 is constantly locked against rotation by the plug projections 51, but rotation of the shaft by the handle 48 will cause the pinion teeth 49 to ratchet over the fixed teeth of the member 50 and to rotate the pinion 19, thereby moving the hammer cylinder 14 downwardly. The hammer cylinder 14 will be locked in any position of adjustment and against lifting by the ratchet teeth, but when pressure is applied to the button 54, this locking connection is interrupted and the cylinder 14 may be moved freely within the fitting bore 18 either toward or away from the anvil block 9. The fitting 16 is normally rigidly clamped to the horizontal frame end 8 by means of the bolt 17, and a pin 57 coacts with a notch in the end of the fitting as shown in Fig. 1, in order to properly position the center line of the cylinder 14 in line with the axis of the vertical frame end 7. The pinion 19 is also preferably provided with spiral teeth which mesh with the inclined teeth 20 on the cylinder 14, and this feature is extremely important since it eliminates play or lost motion between the fitting 16, pinion 19 and cylinder 14 at all times.

During normal operation and use of the improved sheet metal straightener, the dolly block 11 may be withdrawn from the anvil block 9 sufficient to permit these parts to be positioned on opposite sides of the sheet metal work which is to be ironed out or straightened, by utilizing the button 54 and plunger 53 to release the pinion 19 from the member 50, and by subsequently sliding the cylinder 14 manually along the fitting bore 18. When the blocks 9, 11 have been thus positioned below and above the work, these blocks may be brought into operative position with the work, by rotating the pinion 19 with the aid of the handle 48, and the dolly rim or lip 26 may be brought into substantial engagement with the top of the sheet metal about the area which is to be straightened. The ratchet teeth 49 will lock the blocks 9, 11 against subsequent spreading until the release button 54 is pressed. When this adjustment has been properly made, the blocks 9, 11 should be freely slideable along the sheet metal work, and the latter should not be too firmly clamped between the blocks.

As the compressed air is admitted to the passage 36 through the duct 40 and port 39, this air acting upon the upper unbalanced area of the plunger 15 at the top of the passage 36 and upon the upper end of the pin 13, will quickly raise the plunger to admit air to the chamber 41, and this compressed air acting upon the lower face of the plunger 15 will interrupt communication between the port 39 and duct 40 and will establish communication between the duct 40 and the upper chamber 38 through the annular groove 41' of the plunger. The air from within the passage 36 and chamber 37 will then escape through the lower exhaust port 42 to atmosphere, and the compressed air which enters the displacement chamber 38 past the groove 41' will quickly force the plunger 15 downwardly to again cut-off communication between the supply duct 40 and chamber 38 through the groove 41'. The air from within the chamber 38 quickly escapes through the upper exhaust port 43 when the supply is cut-off, thus again permitting the compressed air entering the passage 36 and chamber 37 to elevate the plunger 15. As this cycle of operations is rapidly and automatically repeated, a rapid succession of impulses is delivered to the impact pin 13 and from thence to the dolly block

11, and the air confined in the upper cushioning chamber 35 augments these downward impacts but cushions the return stroke of the plunger 15.

Because of the fact that both of the work engaging blocks 9, 11 are freely rotatable and universally tilttable relative to the C-frame 6, this frame may be utilized to slide the ironing blocks 9, 11 along the curved areas of the work, and may be rotated or tilted in any desired direction without interfering with the force and desirable direction of application of the impacts. During tilting of the frame 6, the annular lip 26 of the dolly block 11 maintains both of the blocks 9, 11 in proper relation to each other and to the surfaces of the work which are being straightened, and the blocks 9, 11 may be advanced along plane, simple curved, or compound curved areas with equal facility. When a job has been completed, either the handle 48 and pinion may be utilized to withdraw the dolly block 11 away from the anvil block 9, or the push button 54 may be used to disengage the pinion driving connection and to permit more rapid manual withdrawal of the hammer cylinder 14 and block 11, and the tool may then be freely removed from the work.

From the foregoing detailed description it will be apparent that my present invention provides an improved sheet metal straightening tool which may be effectively utilized to iron out slight bumps or kinks in sheet metal and to form either a plane or smoothly curved surface at the distorted portions of the work. While I have shown and described a particular type of pneumatic hammer, many other types of these hammers may be utilized, but the mounting of the anvil and dolly block so that these blocks may rotate and tilt universally, is extremely important since this mounting makes it possible to produce smooth ironing of the metal under practically all conditions of operation. By permitting rotation of the manipulating frame 6 relative to the ironing blocks, the frame may be swung in any direction to clear obstructions, and the tilting of the blocks relative to the central axis of the hammer likewise permits swinging of the manipulating frame 6 in any direction while advancing the blocks along the surface being straightened. The lip 26 which coacts with the outer surface of the work acts as a pressure head and is extremely effective in maintaining proper coaction between the inner and outer straightening blocks, and the use of inclined teeth 20 cooperating with a spiral toothed pinion 19 eliminates excessive play or lost motion and retains the blocks 9, 11 in proper position with respect to the surfaces of the work. The lock afforded by the teeth 49 of the pinion coacting with the teeth of the non-rotatable member 50, permits convenient downward adjustment of the cylinder 14 but positively prevents the blocks 9, 11 from separating, unless the release button 54 is pressed, thus preventing the blocks from moving away from the work due to vibration. The drift pin 13 may be quickly removed from or inserted within the bore of the bushing 28, and the blocks 9, 11 may be replaced by other similar blocks adapted to perform different kinds of service. The entire assemblage is obviously extremely simple, compact and durable in construction, and the mechanism has proven highly satisfactory in actual commercial use, especially for the purpose of straightening distorted automobile bodies, fenders and other sheet metal parts.

It should be understood that it is not desired

to limit this invention to the exact details of construction or to the precise mode of use, herein shown and described for various modifications within the scope of the claims may occur to persons skilled in the art.

I claim:

1. In combination, a portable C-shaped frame having upper and lower ends, an anvil universally tiltable upon said lower frame end, a hammer cylinder adjustable with respect to said upper frame end toward said anvil, an impact pin protruding from the lower end of said cylinder, a piston reciprocable within said cylinder to deliver blows to said pin, and a dolly block interposed between said pin and said anvil, said block being universally tiltable relative to said cylinder and pin and having an annular groove facing said anvil and providing a peripheral work engaging lip spaced from and surrounding the

axis of said pin for effecting simultaneous tilting of the anvil and dolly block.

2. In combination, a portable C-shaped frame having upper and lower ends, an anvil universally tiltable upon said lower frame end, a hammer cylinder adjustable with respect to said upper frame end toward said anvil, an impact pin protruding from the lower end of said cylinder, a piston reciprocable within said cylinder to deliver blows to said pin, and a dolly block interposed between said pin and said anvil, said block being universally tiltable relative to said cylinder and pin and having an annular groove facing said anvil and providing a peripheral work engaging lip spaced from and surrounding the axis of said pin for effecting simultaneous tilting of the anvil and dolly block, and said pin being movable along its axis and relative to said dolly block and anvil.

20

ALBERT S. JOHANN.
